2 SHEETS—SHEET 2.

UNITED STATES PATENT OFFICE.

HENRY E. MYERS, OF BOWMAN, NORTH DAKOTA.

EYE TESTER.

1,414,888.

Specification of Letters Patent.

Patented May 2, 1922.

Application filed January 6, 1921. Serial No. 435,452.

To all whom it may concern:

Be it known that I, HENRY E. MYERS, a citizen of the United States, residing at Bowman, in the county of Bowman and

5 State of North Dakota, have invented certain new and useful Improvements in Eye Testers; and I do hereby declare the following to be a full, clear, and exact description of the invention, such as will enable 10 others skilled in the art to which it appertains to make and use the same.

This invention relates to new and useful improvements in eye testers and has for its primary object the provision of means for 15 movably supporting a plurality of eyeglasses containing different lenses between a chart and sight openings, so that a person may be quickly and easily fitted with eyeglasses containing the proper lenses.

20 Another object of this invention is the provision of an eye tester of the above stated character which will be simple, durable and efficient, and which may be manufactured and sold at a comparatively low cost.

25 With these and other objects in view as will become more apparent as the description proceeds, the invention consists in certain novel features of construction, combination and arrangement of parts as will be 30 hereinafter more fully described and claimed.

For a complete understanding of my invention, reference is to be had to the following description and accompanying drawings, in which:—

Fig. 1 is a front elevation, illustrating an eye tester constructed in accordance with my invention,

Fig. 2 is a side elevation illustrating the 40 same and showing the device in an adjusted position,

Fig. 3 is a longitudinal sectional view illustrating the supporting means for the eyeglasses,

45 Fig. 4 is a transverse sectional view illustrating the same and taken on line 4—4 of Fig. 3.

Referring in detail to the drawing, the 50 numeral 1 indicates a casing, the front wall of which is provided with spaced sight openings 2 adjacent its upper end and which receives the inner ends of eye shields 3. The upper portion of the front wall 2 is slightly concaved so as to permit a person 55 to obtain a position in close proximity with the eye shield 3.

The rear wall 4 is hinged to the side wall 5 at lower corners as shown at 6 and said rear wall is adapted to form a chart support by having a plurality of tongues 7 struck out therefrom and which are adapted to be bent over the edges of a card 8 bearing suitable characters. The card 8 is arranged on the rear wall 4 so that the same can be readily read through the sight openings 2.

In operation, the rear wall 4 is moved slightly rearwardly from the casing 1 so as to permit sufficient light to strike the chart and render the same readily readable by way of the eye shield 3.

Segmental shaped plates 9 are pivoted to the side walls 5 at their rear upper corners and are connected by a top wall 10. The segmental plates 9 have formed upon their curved edges right angle extending tongues 11 provided with slots 12 to receive the ear engaging pieces 13 of spectacles or eyeglass frames 14. The ear engaging pieces also engage curved retaining members 15 secured to the plates 9. The curved edges of the plates 9 are arranged in close proximity to the front wall 1 so that the various spectacle or eyeglass frames will be supported in rear and in close proximity to the sight openings. The plates 9 are connected by suitable handles 16 so that said plates may be adjusted for bringing the various eye-glass or spectacle frames in alignment with the sight openings. The spectacle 90 or eye-glass frames are adapted to contain various kinds of lenses so that on adjusting the plates 9 the proper lenses may be brought in rear of the sight openings and the person looking through the sight openings at the 95 chart may readily determine the proper lenses.

A flange 17 is formed on the forward edge of the top wall 10 and projects slightly beyond the front wall so that the same may 100 be readily gripped for raising the top wall and swinging the plates 9 on their pivots when not desiring to employ the handle.

A suitable partition 18 is located in the lower portion of the casing 1 to form an auxiliary compartment 19 in which various articles such as different kinds of lenses and eyeglass frames may be stored.

Any desired type of illuminating means may be placed within the casing for the 110 purpose of placing the proper illumination on the chart.

22
While I have shown and described the preferred embodiment of my invention, it will be understood that minor changes in construction, combination, and arrangement 5 of parts may be made without departing from the spirit and scope of the invention as claimed.

What is claimed is:

An eye tester comprising a support including side, front and bottom walls, said front wall having sight openings adjacent its upper end and a depression between said openings to receive the nose of a person, a top wall pivoted to the side walls, a rear wall pivoted to the side walls adjacent their 10
15

lower edge and carrying a chart, flanges formed on the rear walls and adapted to have frictional contact with the side walls to hold said rear walls in adjusted positions, segmental shaped plates secured to 20 the top wall and movable within the side walls, and means supporting eye glasses on the curved edges of said plates.

In testimony whereof I affix my signature in presence of two witnesses.

HENRY E. MYERS.

Witnesses:

ROGER I. LEE,
N. BODIEN.
